United States Patent Office

Des. 194,625

Patented Feb. 19, 1963

194,625

CUP DISPENSER

Charles L. Metzler, Alpine, N.J., and John D. Wark,
Freeport, N.Y., assignors to American Can Company,
New York, N.Y., a corporation of New Jersey

Filed Aug. 31, 1961, Ser. No. 66,574

Term of patent 14 years

(Cl. D52—2)

Fig. 1

Fig. 2

Fig. 3

Fig. 4

FIG. 1 is a plan view of the cup dispenser showing our new design;

FIG. 2 is a side perspective view thereof;

FIG. 3 is a front perspective view thereof with a paper cup shown in broken lines for purposes of illustration;

FIG. 4 is a rear perspective view thereof.

We claim:

The ornamental design for a cup dispenser, substantially as shown and described.
